UNITED STATES PATENT OFFICE.

OLOF JOHANSON, OF NEW YORK, N. Y.

STEM-WINDING DEVICE FOR WATCHES.

SPECIFICATION forming part of Letters Patent No. 351,919, dated November 2, 1886.

Application filed February 26, 1886. Serial No. 193,335. (No model.)

To all whom it may concern:

Be it known that I, OLOF JOHANSON, of the city, county, and State of New York, have invented a new and useful Improvement in Keys for Stem-Winding Watches, of which the following is a full, clear, and exact description.

Reference is to be had to the accompanying drawings, forming a part of this specification, in which similar letters of reference indicate corresponding parts in both the figures.

Figure 1 is a face view of a stem-winding watch, and showing a key applied to it. Fig. 2 is a perspective view of the key.

The object of this invention is to provide keys for stem-winding watches, by the use of which the said watches can be easily and quickly wound.

The invention consists in a key constructed with a ring and a U-shaped loop bent three times at right angles laterally, to adapt it to receive and engage with the crown of a stem-winding watch, as will be hereinafter fully described.

A represents the watch-case, B the stationary stem, and F the guard-ring hinged to the said stem.

C is the rotary crown, which is attached to a rotary stem or shaft connected with the winding mechanism in the ordinary manner.

The key is made with a ring, D, of such a size as to readily receive a finger, and with a U-shaped loop, E, which is bent three times at

right angles laterally, as shown in Figs. 1 and 2, to form a recess, which can be passed over the crown C, and will grasp the said crown, 35 so that it will be turned to wind up the watch by turning the said key.

In using the key the bent or recessed loop E is sprung upon the crown C, as shown in Fig. 1, the forefinger is inserted in the ring 40 D, and the key is operated as a crank to turn the crown C and wind the watch. When the watch is wound, the key is sprung off the crown C.

The key D E can be made of spring-wire or 45 other suitable material, and the ring D can be a close ring, or an open ring, as shown in Fig. 2, as may be desired. The latter construction is preferred, as allowing the key to be readily attached to a watch-guard.

Having thus fully described my invention, I claim as new and desire to secure by Letters Patent—

A key for stem-winding watches, constructed with a ring, D, and a U-shaped loop, E, 55 bent three times at right angles laterally, substantially as herein shown and described, whereby it is adapted to receive and engage with the crown of a stem-winding watch, as set forth.

OLOF JOHANSON.
